UNITED STATES PATENT OFFICE.

JOHN HENRY ROBERTS, OF SHELBYVILLE, ILLINOIS.

RAIL-JOINT.

SPECIFICATION forming part of Letters Patent No. 694,993, dated March 11, 1902.

Application filed September 13, 1901. Serial No. 75,341. (No model.)

To all whom it may concern:

Be it known that I, JOHN HENRY ROBERTS, a citizen of the United States, residing at Shelbyville, in the county of Shelby and State 5 of Illinois, have invented certain new and useful Improvements in Rail-Joints, of which the following is a specification.

This invention relates to improvements in rail-joints; and the main object of my invention is the provision of a joint which will dispense with fish-plates and provide a means of connection which will make the joint more firm and yet allow for the contraction and expansion of the metal.

Another object of my invention is the provision of a joint for metal rails which may be used upon railroads or for beams in metal structures, as the joints thereof are virtually self-supporting and are provided with auxiliary means to prevent the joint from in any way twisting or turning.

To attain the desired objects the invention consists of a rail-joint embodying novel features of construction and arrangement of parts, substantially as disclosed herein.

In the drawings, Figure 1 is a perspective view of two rails provided with my improved joint. Fig. 2 is a similar view of one end of a rail. Fig. 3 is a section taken at the junction of the top of the rails, and Fig. 4 is a section taken at the junction at the bottom of the rails.

Referring thereto, A designates one section of the rail, and B the other section. The rail A is provided with the usual base C and the flat top portion D, said base and top portion being connected by the vertical supporting-strip E. The end of this rail is constructed so that the top rail portion is cut away at F and the base 35 at G, a point a distance beyond the end of the top portion, the end of the strip E projecting beyond the base and being provided with the lower curved strip H to rest upon the flange of the base J of the section B. The section B is somewhat similar in construction, except that the end of the top portion is cut away, as at K, a point beyond the cut-away portion L of the base. The extension M is provided with the lower curved strip N, which 40 is adapted to rest upon the opposite side of the base of the adjacent rail from the other strip. The extension ends of each section 45 gradually taper or incline outward from the

body, so that when they interlock, as shown in Fig. 1, they take the place of the common fish-plate and form a tie for the ends of the rails as well as a brace to prevent the ends from sagging or twisting under a great weight. These extensions are further provided with the openings O to receive bolts P, so that the 55 ends of the sections may be securely held together. By having the meeting ends of the top portions out of line with the meeting edges of the bases the strength of the joint is more effective and less liable to twist or sag 60 as they assist the extensions to a great extent 65 and also act as braces for the joint.

By this construction of joint an absolutely-noiseless joint for railroad-rails is produced, as fish-plates are dispensed with and sagging 70 of the rails is prevented, as the whole joint supports and braces itself.

It is evident that I provide a joint for metal rails which is the embodiment of simplicity, durability, and inexpensiveness, thus 75 producing a thoroughly efficient and practical joint.

What I claim as new is—

The herein-described joint for the ends of two rails or beams, the end of one having a 80 flanged base, a vertical strip or web connected to the base, and a top portion supported by the strip, said strip having its end extending beyond the base and top portion, and said end of the base extending beyond the top portion; 85 and the end of the other having a flanged base, a vertical strip or web connected to the base, a top portion supported by the strip, said strip extending beyond the base and top portion and said top portion extending be- 90 yond the base; and a lower curved strip connected to both ends provided upon opposite sides of the lower edges of the strips to rest upon the upper portions of the bases; whereby the ends of the strips interlock, the meeting edges of the top portions and bases are out of line with each other, and the lower curved strips rest upon opposite sides of the vertical strip of the bases to prevent the joint 95 from twisting or turning.

In testimony whereof I affix my signature in presence of two witnesses.

JOHN HENRY ROBERTS.

Witnesses:

W. D. ROBERTS,
FRANCIS M. STURGIS.
